AUTOMATIC SYSTEM FOR WEB LENGTH MEASUREMENT

Solomon Steinberg, New York, N.Y.
 (108-20 68th Road, Forest Hills 75, N.Y.)
 Filed Apr. 11, 1962, Ser. No. 186,766
 14 Claims. (Cl. 33-127)

In certain industrial uses it is highly desirable to measure the length of a long continuous web without stopping the movement of the web with a consequent loss of machine production of web product.

Thus, for example, in the case of newspaper, magazine, form, and similar printing, paper coating, and other "conversions," the paper stock is supplied as large heavy rolls, and it is important that a predetermined paper weight-area ratio be maintained. As compared to a standard or special basis weight, if the paper is too light per unit of area, undesirable paper qualities may prevail, such as low opacity, low strength, etc.; and, on the other hand, if the paper is too heavy per unit of area, the cost of the complete newspaper, for example, becomes higher. It is possible to measure the length of the paper web in the roll by unrolling the roll and rewinding it and then making a calculation against the stated or weighed weight. This is time consuming and inconvenient.

It is therefore among the objects of the present invention to measure the length of the web in a given roll, while the roll is being consumed as it is being unwound in the press.

In modern high-speed newspaper printing presses a plurality of rolls are mounted on a reel spider combined with a device which automatically connects the end of one roll with the beginning of the next roll. Such devices are referred to as autopasters, and the connecting operation may be automatically or manually initiated.

It is another object of the present invention to utilize the controlling impulses for the device which interconnects the web ends, or the actions of the said device itself, to consecutively discontinue and initiate the action of a plurality or a series of web length measuring elements.

Since ruptures in the web do occur from time to time, rejoining of the ruptured ends, or re-webbing, becomes necessary. The damaged portion of the web is removed, and thus the original weight-web length ratio becomes inaccurate and perhaps valueless. It is therefore among the objects of the present invention to deactivate the particular web length unit counter associated with the damaged or shortened web roll, or to activate indicating means which show that the reading of a particular web length unit counter is to be disregarded.

Since minor variations may occur, more accurate figure values are obtained by averaging the readings of a plurality of web length unit counts.

In the drawing, in which similar reference characters designate corresponding parts in the several views of each embodiment:

FIGURE 1 is a schematic view showing a first embodiment of the invention.

FIGURE 2 is a fragmentary elevational view, partly schematic, of the first embodiment.

FIGURE 3 is a circuit schematic of the first embodiment.

FIGURE 12 is a circuit schematic of the fourth embodiment.

FIGURE 12A is an enlarged detail view of a portion of FIGURE 12.

While, as I have indicated, the present invention may be used with various web feeding and transfer devices, I have chosen for example to show the same as embodied in a printing press 11 for printing newspapers or the like.

As seen in FIGURE 1, a system, generally indicated by reference character 10, is adapted for use and coacts with one web 12. In FIGURE 1 there are seen five webs 12, 12b, 12c, 12d and 12e; and the additional systems therefore, corresponding to 10, are disposed rearward thereof and not seen. Any desired number of webs may be used with corresponding systems. These systems are substantially identical so that a detailed description of one will suffice for all.

The web 12 is supplied from the consecutive interconnection of a plurality of rolls 14, 14b and 14c by an autopaster 16, as the rolls carried by the paper supply-carrying spider 18 are rotated into proper position. After

leaving the autopaster 16, the web 12 may pass upward through the pressroom floor 20, about the plate cylinders 22 (inked by ink distribution rollers 24 and fountains 26), impression cylinders 28, over and down the former 30, into the folder 32 and onto the delivery conveyor 34. This construction is well-known in the printing press art so that more detailed description thereof is not necessary for an understanding of the invention. As indicated, various types such as Goss, Scott, Wood, Hoe and Cline are well-known, among others. The autopasters can be manually or automatically operated, and it is the impulse generated thereby, which may be mechanical, electrical, pneumatic, hydraulic, or otherwise, which initiates the counting action on a given web length unit counter and/or causes a shift to another web length unit counter.

On the panel 40 are mounted a plurality of web length unit counters 50, 50b and 50c and web rupture indicating means 48, 48b and 48c. The counters are readable through the windows 42, and print their readings on tapes 44. In accordance with the present invention, the actual precise length of the roll 14 will appear through a window 42 on counter 50 and will appear in print on a tape 44 therebelow, the instant that roll 14 is consumed. If the web of roll 14 should break or be damaged so that the removal of a part thereof is necessitated, the counter would no longer give a true reading of original roll length and its reading must be disregarded. Should this occur, the signal light or similar indicating means 48 will be activated, a colored or opaque pane 84 will obscure the reading through window 42, and the printing on tape 44 will appear in a distinctive color, such as red.

As soon as roll 14b is connected into the continuous web by autopaster 16, the next counter 50b starts counting and the operation, just described, is repeated. Similarly the actual length of roll 14c is counted on counter 50c. Depending on the length of the run or similar considerations, additional counters 50 and additional rolls 14 may be incorporated in the system 10. The counters 50 may be calibrated to read in feet or other desired units of measurement.

Turning to FIGURE 4, the counter 50 may include a housing 52, and between the vertical side walls 54 is journaled a horizontal shaft 56 which forms the support

for the counter wheels 58 and 60, which are the reading and printing wheels, respectively. The well-known operating mechanism 62 for driving the counter wheels is preferably electrically actuated (conductors 64 and 66, FIGURE 3), while resetting to zero is accomplished by the upward movement of lever 68 by slideable rod 70 of solenoid 72 when reset winding 74 is energized. The rod 70 is frictionally retained in displaced positions thereof so that the magnetic slug thereon is shifted up by winding 74 and down by winding 88.

A normal or black ink printing ribbon 80, a disregard or red ink printing ribbon 82, and a colored pane 84 are carried by the cradle 86, pivotally mounted on shaft 56, and adapted to move clockwise (FIGURE 4) upon energization of the disregard winding 88, to a position where the ribbon 82 is directly opposite the printing platen 76 with the tape 44 therebetween, and the pane 84 lies between window 42 and the wheels 58, and cradle arm 87 closes switch 83 which closes circuit to activate indicator means 48.

The platen 76 is part of the armature 77 of solenoid 78 which, when energized, elevates platen 76 against gravity to compress tape 44 against wheels 60 with either ribbon 80 or 82 therebetween. When de-energized, armature 77 descends operating the tape advancement means 90 including pawl 92, ratchet wheel 93, drive roller 94 and pressure roller 95.

A line source of electrical energy (not shown) is connected across conductors 102 and 103. The counter 50 is advanced by the counter advancing circuit, with energy traveling along conductor 102 to switch 104, conductor 106, selector switch 108, conductor 64, to counter 50, conductor 66, and conductor 103.

One or more counter cams 96 are mounted on a part of the press 11 which moves in direct correlation to the lineal surface movement of the web 12. Thus, for example, a cam 96 may take the form of a protuberance on any drum or cylinder which drives or is driven by the web. Thus, impulses for the counter may be taken from any active drawing or feeding roller which rotates in correlation to the web movement to reflect web length units, and this structure may be integral with the press or may be an attachment. The impulse may be taken from a point at the folder 32 so as to get a plural or parallel count for a number of webs simultaneously, and a break in any web will indicate that that count is to be disregarded. Furthermore, axial movement of an ink distributing roller which is timed to a web feeding roller can be used to intermittently close a switch 13 (FIGURE 1) to generate pulses from web 12 to the counters 50. Thus by way of example, I have shown the cams 96 on an impression cylinder 28, and the counter 50 is geared or otherwise adjusted to read in lineal distance precisely equated to the paper contacting periphery of the cylinder 28. As the press 11 operates and the web 12 travels therethrough, the counter 50 will add the total length of the web.

The autopaster unit 17 of the system 10 is located on the press 11 and is connected at its terminals 100 and 101 to conductors 102 and 105, respectively. When the roll 14 becomes exhausted, it will be connected to the beginning of roll 14b by autopaster 16 which usually is electrically operated by an impulse in circuit 110 which powers solenoid 112 and shifts the autopaster arm 116 to which is connected known structure such as brush and knife (FIGURE 1). The circuit 110 is completed by suitable known sensing means 111 such as a feeler on the expiring roll, projecting tab on the paper edge at the roll end, a photocell arrangement, a conducting area on the web, or the like, or manually.

Thus the roll 14 having been consumed and its length having been measured, the impulse in the circuit 110 also powers solenoid 114 whose pawl armature 115 advances the selector switch 108 to the next position so that conductor 106 now feeds conductor 64b and counter 50b. This will continue in like manner for the desired num-

ber of rolls 14 and counters 50 in the group or run. After the group or run is completed, the results on the counters 50 may be read and recorded and may be automatically printed, and the counters reset. This is accomplished by manually closing the reset switch 97 which first completes the circuit to the printing solenoid 78 via conductors 102, 118 and 103; and then completes the circuit to the reset winding 74, in solenoid 72, via conductors 120 and 103, as well as the circuit to the selector switch 108 return solenoid 109 via conductors 122 and 103. When energized, solenoid 109 pulls armature 109' thereby disengaging pawl 113 which allows spring 124 to rewind the switch arm in switch 108 to its original starting position.

The web break detector unit 15 of the system 10 is located on the press 11 and is connected at its terminals 130, 131 and 132 to conductors 102, 134 and 136, respectively. Any number of units 15 may be used, connected in series so that the greater the number of sensing points, the less the probability of a break to be undetected and/or the more nearly accurate will be the readings. Thus the roller sensing elements 138 are preferably located at a bearing on each of the rollers or cylinders which would or could be removed during normal press operation, such as changing or modifying printing cylinders or plates during the unwinding of a roll 14 to make repairs, or adjustments, or to change editions. The elements 138 include a relatively fixed contact 139 and movable spring contacts 140 which open when a roller or cylinder is removed, thereby breaking the circuit and preventing a false indication of rupture caused by slack in the web 12 allowing the feeler shoe 142 to drop, which would close the circuit from conductor 102 through conductor 144, conductor 145, switch 146, conductor 148, switch 150, and conductor 152. Similarly the feeler shoes 142 are preferably located at all spans of the web 12 between pressure contacting rollers, so that a break in the web will be immediately detected.

The motor 154 which drives the press 11 is connected to conductor 103 through switch 156 and to conductor 136. This enables switch 158 to stop motor 154 if shoe 142 drops because of web breakage.

Switch 160 has an arm 161 which is fixed on shaft 107, as is the arm 162 of switch 108, so that said arms move in unison. Therefore, in the event of a web rupture, a circuit is completed through switch 146, conductor 148, switch 150, conductors 152 and 134, arm 161, conductor 164, winding 88, and conductor 103. This pushes cradle arm 87 down as previously described and switch 83 closes a circuit between conductor 102, indicator means 48, and conductor 103, activation will be in unison. In repair, usually the damaged section of the web is cut out and the remaining free ends are joined. This makes the reading on that particular roll inaccurate. Because the rod 70 (FIGURE 4) is frictionally retained in shifted positions thereof, the means 48 will stay lit, and ribbon 82 and pane 84 will stay in the "disregard" position until reset switch 97 is closed.

Turning now to the second embodiment of the invention, as shown in FIGURES 6 and 7, for the purpose of avoiding needless repetition certain of the parts corresponding to the first embodiment are given the same reference characters with the addition of a suffix "e."

The second embodiment differs from the first embodiment principally in provision of a single counter without automatic reset, manual resetting being provided.

Thus after a reset (the closing of switch 97e), switch 156e is closed starting motor 154e. At the end of the first roll, the autopaster unit 17e sends an impulse to solenoid 78e causing the total then appearing on the counter 50e to print on tape 44e, and this will repeat at each roll end. If a break has occurred, the print out will appear in red in the tape 44e and the indicated linear distance between the red number and the next preceding number will be disregarded. At the end of the run, or roll group, switch 97e is again closed, which resets the sys-

tem for beginning anew. The arm 68e may directly reset the counter, or, where the counter is reset by a motor 166e, arm 68e may close switch 168e in circuit to such motor as shown in FIGURE 7.

In the third embodiment of the invention, as seen in FIGURES 8 to 10, inclusive, repetition is again avoided by using certain reference characters of corresponding parts in the prior embodiments with the suffix "i."

The third embodiment differs from the first and second embodiments primarily in the provision of a single counter with automatic reset, manual resetting being also available.

The automatic reset circuit includes a switch 197i which is mounted on the platen 76i, and which closes the circuit during downward travel of the platen 76i after the printing impression has been completed. Switch 197i includes a pivotal contact finger 198i, swingable between two detents. The upper surface of finger 198i has an insulating member which prevents contact of the conducting portion 199i during upward travel. During downward travel the portion 199i wipes the relatively stationary contact point 200i, which is resiliently mounted on spring 201i.

Thus in the third embodiment the counter 50i will print when each roll is consumed, and the reading will be the length of each roll as consumed (except when the "disregard" circuit causes printing in a different color).

Turning to the fourth embodiment of the invention, as seen in FIGURES 11 and 12, for the purpose of avoiding needless repetition, certain of the parts corresponding to the prior described embodiments are given the same reference characters with the addition of a suffix "i."

Where the web speed is relatively fast and the counter reset time is not instantaneous, a loss in counting length may require rapid shifting between two counters with the reset taking place in one counter during inactivity of the other counter. This is what the fourth embodiment provides.

With the step switch 214i and the shifting switch 210i in the position shown in FIGURE 12, the cams 96i act on switch 104i to intermittently close the circuit via conductors 64i and 66i to actuate counter 50i. A pulse from the autopaster unit 17i, via conductors 212i and 213i, energizes step relay 214i, which shifts the line voltage previously connected to winding 216i of switch 210i (via conductor 240i) to winding 218i (via conductor 242i), causing switch 210i to move to the right in said figure.

This does four operations. Arm 220i disconnects counter 50i and connects counter 50bt in circuit with switch 104i, and conductors 102i, 64bt and 66i. Arm 222i moves to disconnect printer solenoid 78i from the circuit 102i, 100i, 101i, 118i, 119i, 103i to connect solenoid 78bt via conductor 119bt. The contact 224i is elongated to allow sufficient time for solenoid 78i to print, but by the time arm 222i reaches contact 226i, the pulse has discontinued and solenoid 78bt cannot print. Arm 228i, which via conductors 102i, 134i, 164i and 103i had completed the circuit from web break detector unit 15i to disregard winding 88i, now shifts to 164bt to complete the circuit from unit 15i to disregard winding 88bt. Arm 230i (after arm 220i has decontacted conductor 64i) closes the circuit 102i, 120i, to reset winding 74i by contacting the upper contact on the switch cam 231i (FIGURE 12A), so that counter 50i may be reset independently of the initiation of operation of counter 50bt.

The next autopaster pulse will travel to step relay 214i, causing it to send the line voltage to winding 216i, via conductor 240i, thereby pulling shifting switch 210i back to its original position in FIGURE 12. On its trip back the resilient pivotal finger 232i on the end of arm 230i contacts the lower conductive surface of switch cam 231i to provide resetting of counter 50bt.

I wish it to be understood that I do not consider the invention limited to the exact details of structure shown and described in this specification, for obvious modifications will occur to a person skilled in the art to which the invention pertains.

I claim:

1. A system for web length measurement for use with a continuous web treating machine having web feed means and means to interconnect web portions, comprising: measuring means on said web feed means supplying an impulse for a predetermined length unit of said web; a web length unit counter; said measuring means actuating said counter; said means to interconnect being connected to said counter to stop the counter, whereby total continuous web length may be read off said counter.

2. A system for web length measurement for use with a continuous web treating machine having web feed means and means to interconnect web portions, comprising: measuring means on said web feed means supplying an impulse for a predetermined length unit of said web; a web length unit printing counter; said measuring means actuating said counter; said means to interconnect being connected to said counter to cause the counter to print, whereby total continuous web length may be read off said counter.

3. A system for web length measurement for use with a continuous web treating machine having web feed means, a plurality of independent web portions, and interconnection means for joining the end of one web portion to the beginning of the next web portion, said system comprising: measuring means associated with said feed means providing an impulse for each predetermined unit of web length, as the web travels along said feed means; a web length unit printing counter with error indicating means; web break sensing means connected to said indicating means; a pair of web length unit counters; and means actuated by the interconnection means to alternately associate the said measuring means with said counters in turn.

4. An automatic system for web length measurement for use with a continuous web treating machine, having a web feed means, a plurality of independent rolls of web portions, means to consecutively introduce said web portions into said web feed means, and interconnection means for joining the end of one web portion to the beginning of the next web portion, said system comprising: measuring means on said feed means providing an impulse for each predetermined unit of web length as the web travels through said feed means, a plurality of web length unit counters, said measuring means being associated with said counters whereby the total web length units of the first web portion will be indicated on the first web length unit counter and the total length units of each of the remaining web length portions will be indicated selectively and separately on the remaining web length unit counters.

5. An automatic system for web length measurement for use with a continuous web treating machine, having a web feed means, a plurality of independent rolls of web portions, means to consecutively introduce said web portions into said web feed means, and interconnection means for joining the end of one web portion to the beginning of the next web portion, said system comprising: measuring means on said feed means providing an impulse for each predetermined unit of web length as the web travels through said feed means, a plurality of web length unit counters, said measuring means being associated with said counters whereby the total web length units of the first web portion will be indicated on the first web length unit counter and the total length units of each of the remaining web length portions will be indicated selectively and separately on the remaining web length unit counters, and means to deactivate a counter when the associated web length section is broken.

6. An automatic system for web length measurement

for use with a continuous web treating machine, having a web feed means, a plurality of independent rolls of web portions, means to consecutively introduce said web portions into said web feed means, and interconnection means for joining the end of one web portion to the beginning of the ext web portion, said system comprising: measuring means on said feed means providing an impulse for each predetermined unit of web length as the web travels through said feed means, a plurality of web length unit counters, said measuring means being associated with said counters whereby the total web length units of the first web portion will be indicated on the first web length unit counter and the total length units of each of the remaining web length portions will be indicated selectively and separately on the remaining web length unit counters, and means to deactivate a particular counter when a particular web length section is broken.

7. In a system for web length measurement for use with a continuous web treating machine using more than one web portion: a web length unit counter; means to record a reading on said counter; means to interconnect web portions ends; and means to actuate said means to record in correlation with the interconnection of said web portions by said means to interconnect.

8. A system for web length measurement for use with a continuous web treating machine having web feed means, a plurality of independent web portions, and interconnection means for joining the end of one web portion to the beginning of the next web portion, said system comprising: measuring means associated with said web feed means providing an impulse for each predetermined unit of web length, as the web travels along said web feed means; a web length unit counter, independent web break indicating means in said counter, positively registering an error signal in said counter, and web break sensing means connected to said indicating means, activating said indicating means upon web rupture, whereby after the web rupture has occurred and been mended, and the remainder of the roll consumed, the reading at the termination of the roll count will show the error.

9. A system for web length measurement for use with a continuous web treating machine having web feed means, a plurality of independent web portions, and interconnection means for joining the end of one web portion to the beginning of the next web portion, said system comprising: measuring means associated with said web feed means providing an impulse for each predetermined unit of web length as the web travels along said web feed means; a web length unit printing counter; independent web break indicating means in said counter positively registering an error signal in said counter, and web break sensing means connected to said indicating means, activating said indicating means upon web rupture, whereby after the web rupture has occurred and been mended, and the remainder of the roll consumed, the reading at the termination of the roll count will show the error.

10. A system for web length measurement for use with a continuous web treating machine having web feed means, a plurality of independent web portions, and interconnection means for joining the end of one web portion to the beginning of the next web portion, said system comprising: measuring means associated with said web feed means providing an impulse for each predetermined unit of length as the web travels along said feeding means; a web length unit printing counter, error indicating means in said counter; web break sensing means connected to said indicating means, activating said indicating means upon web breakage; and means actuated by said interconnection means to cause the counter to print.

11. A system for web length measurement for use with a continuous web treating machine having web feed means, a plurality of independent web portions, and interconnection means for joining the end of one web portion to the beginning of the next web portion, said system comprising: measuring means associated with said web feed means providing an impulse for each predetermined unit of web length as the web travels along said feed means; a web length unit printing counter; error indicating means in said counter; web break sensing means connected to said indicating means, activating said indicating means upon web breakage; and manual means to activate said interconnection means and to simultaneously cause the counter to print.

15. 12. A system for web length measurement for use with a continuous web treating machine having web feed means, a plurality of independent web portions, and interconnecting means for joining the end of one web portion to the beginning of the next web portion, said system comprising: measuring means associated with said web feed means providing an impulse for each predetermined unit of web length, as the web travels along said web feed means; a pair of web length unit counters, and means actuated by said interconnection means to alternately operatively connect the said measuring means with said counters in turn, whereby total continuous web length may alternately be read off said counters.

20. 13. A system for web length measurement for use with a continuous web treating machine having web feed means, a plurality of independent web portions, and interconnecting means for joining the end of one web portion to the beginning of the next web portion, said system comprising: measuring means associated with said web feed means providing an impulse for each predetermined unit of web length, as the web travels along said web feed means; a pair of web length unit counters, and means actuated by said interconnection means to alternately operatively connect said measuring means with said counters in turn, said counters each having independent error 25 indicating means which positively registers an error signal in said counters, and web break sensing means connected to said indicating means, activating the same upon web rupture, whereby after the web rupture has occurred and been mended, and the remainder of the roll consumed, the reading at the termination of the roll count will show the error.

30. 14. A system for web length measurement for use with a continuous web treating machine having web feed means, a plurality of independent web portions, and interconnection means for joining the end of one web portion to the beginning of the next web portion, said system comprising: measuring means associated with said web feed means providing an impulse for each predetermined unit of web length as the web travels along said feed means; a pair of web length unit printing counters, means actuated by said interconnection means to alternately operatively connect said measuring means with one of said counters and causing the other counter to print, independent error indicating means in each of said counters positively registering an error signal in said counters, and web break sensing means connected to said indicating means, activating the same upon web rupture, whereby after the web rupture has occurred and been mended, and the remainder of the roll consumed, the reading at the termination of the roll count will show the error.
